SHOCKPROOF X-RAY APPARATUS

Montford Morrison, Montclair, N. J., assignor to
Westinghouse X-Ray Company, Inc., a corpora-
tion of Delaware

Application February 1, 1933, Serial No. 654,654

11 Claims. (Cl. 250—34)

My invention relates to electron discharge apparatus and particularly to X-ray apparatus wherein the danger of an operator or patient accidentally contacting any high voltage parts is entirely eliminated.

5 In such apparatus of the prior art it is customary to encase the X-ray tube and the high tension source of energy therefor in a container and immerse the same in a body of insulating and cooling material, such as oil. This latter 10 material, which has a higher dielectric strength than air, enables the spacing between all high tension carrying parts to be considerably less than would be required for the same applied voltage in air and consequently the X-ray tube 15 may be materially shortened. As the X-ray tube necessarily generates appreciable heat during its operation this may be dissipated somewhat by the envelope to the surrounding insulating and cooling medium and in addition it 20 may be more readily dissipated by providing the anode stem of the tube with a cooling radiator likewise immersed in this body.

This results in a rugged and compact unit of a portable nature free from the danger of electrical shocks and capable of supplying the X-ray tube with relatively high energy. However, an objectionable feature is inherent in this type 25 of shockproof unit due to the necessity for the X-rays radiating from the tube to penetrate the insulating and cooling medium surrounding the tube. This medium accordingly acts as a filter and affects to a great extent the quality 30 of the X rays to which a patient or a sensitized film is subjected.

35 In accordance with my present invention I retain all the essential features requisite in shockproof X-ray apparatus by immersing the high tension source and all high tension terminals in oil and utilize a foreshortened tube as 40 in prior art devices to eliminate the danger of shocks to operator or patient. In addition I obviate the objectionable feature of allowing the oil surrounding the high tension parts to act 45 as a filter for the X-rays emanating from the tube by disposing that portion of the envelope through which the X-rays emanate from the anode target exteriorly of the casing or tank encasing the high tension parts of the apparatus.

50 For a better understanding of the novel features of my present invention reference may be had to the accompanying drawing wherein

55 Figure 1 is a sectional view of a shockproof unit constructed in accordance with my invention with a portion of the apparatus shown in

diagrammatical form for the purposes of simplicity.

Figure 2 is an elevational view on an enlarged scale of the tube supporting structure shown in Fig. 1 with a part broken away to better illustrate the several parts.

Figure 3 is an elevational view on a slightly enlarged scale of a modification of the tube supporting structure of Figure 1, and

Figure 4 is an elevational view on a slightly enlarged scale of still another modification of the tube supporting structure with a part broken away for the purposes of better illustration.

Referring now to the drawing in detail I have shown in Figure 1 a casing 5 which may be of a light durable metal and suitably connected to ground as at 6. A high tension transformer diagrammatically illustrated, having a low tension winding 7 and a high tension secondary 8, is housed within the casing 5 and immersed in a cooling and insulating medium, such as oil 9. The primary winding 7 receives electrical energy from a suitable source of alternating current of the usual commercial potential through a pair of conductors 10 and 12 which pass through a suitable insulating block 80 or terminal 13 provided in the wall of the casing 5.

An X-ray tube having a vitreous evacuated envelope 14, a thermionic cathode 15, and an anode 16 is secured to the casing 5, in a manner 85 to be hereinafter more fully described, with a portion of the envelope disposed exteriorly of the casing and the remainder thereof disposed interiorly of the casing and immersed in the body of cooling and insulating material 9. A cooling radiator 17 is secured to the terminal of the anode 16 which extends exteriorly of the evacuated envelope and is accordingly immersed 90 in the cooling and insulating medium 9 for the purpose of transmitting the heat generated during operation of the tube to this latter medium.

A low tension transformer 18, having a primary winding 19, which may be connected to the same commercial source of electrical energy as the primary winding 7; and a secondary winding 20, supplies heating current to the cathode 15 through a pair of conductors 21 and 22 which are connected to the cathode terminals 23 and 24 of the X-ray tube disposed exteriorly of the envelope and casing.

One end of the high tension secondary winding 8 is connected to the anode terminal, which constitutes the radiator 17, by means of a conductor 25 disposed within the casing and the

remaining end of the high tension secondary 8 is suitably connected to the metallic tank 5 through a conductor 26. The high tension circuit for supplying discharge energy to the X-ray tube is completed by means of a conductor 27 which connects the casing 5 to the cathode heating source 20.

In the operation of my unit a control stand is normally employed containing the switches 10 which connect the primary windings 7 and 19 of the high and low tension transformers, respectively, to the commercial source of supply. The low tension cathode heating transformer may be an integral part of the control apparatus 15 separated from the shockproof unit as shown diagrammatically in Figure 1 in order to reduce the weight of the unit itself. However, should it be preferred this transformer may be placed within the casing 5 and immersed in the cooling 20 and insulating medium in the same manner as the high tension transformer.

In supporting the X-ray tube to the container, as shown in Figures 1 and 2, a flange 28 of a suitable material, such for example as that of the casing 5, provided with a laterally extending frusto-conical portion, surrounds the envelope 14 adjacent the cathode. The smallest internal diameter of this frusto-conical portion is substantially equal to that of the diameter of the envelope and increases in diameter toward the base or collar portion of the flange 28.

A suitable oil resisting cement 29, having a coefficient of expansion simulating that of the vitreous envelope 14, is disposed in the space 35 between the envelope and the frusto-conical portion of the flange and unites the two rigidly together thus making the flange an integral part of the tube. The tube is then secured to the casing 5 by suitable fasteners, such as studs 40 30, extending outwardly from the casing and adapted to pass through openings provided in the flange 28 with the latter rigidly secured to the casing by nuts 32. This construction allows the ready removal of the tube for replacement or 45 repair without disturbing any other portions of the apparatus. In order to make the connection of the flange to the casing oil tight I may provide a suitable gasket (not shown) or run a thin film of solder or other metal around the 50 edge of the flange where it contacts the casing.

In the particular type of X-ray tube I have illustrated the X-rays emanate from the bulbous end of the envelope 14 adjacent the cathode thus disposing that portion of the envelope from 55 which X-rays emanate during operation of the tube exteriorly of the casing where it is entirely free from oil which would otherwise act as a filter and affect the quality of the X-rays generated. The remainder of the envelope 14 together with the cooling radiator 17 is disposed 60 interiorly of the casing and thus immersed in the cooling and insulating material. The heat generated during operation of the tube is transmitted to the cooling and insulating medium 9 through the walls of the envelope as well as by the radiator 17 resulting in effective cooling and the usual efficient operation of the tube.

Moreover, the high tension terminals and all connections carrying a potential above ground, such for example as the conductor 25 and the anode terminal constituting the radiator 17, are immersed in the cooling and insulating medium having a higher dielectric strength than air. This enables the spacing between these high potential parts and the grounded casing

5 and cathode terminals 23, 24, between which is the full potential of the secondary winding 8, to be considerably reduced over that required for an X-ray tube operated in air with the same applied voltage. Accordingly the X-ray tube itself may be of reduced size as a lesser spacing is required between its respective terminals.

The modifications of my invention shown in Figs. 3 and 4 differ from that just described merely in the manner of supporting the X-ray tube from the casing and in all other respects the construction and arrangements of the various parts are identical. In Fig. 3, I have shown a skirt 33 of the same vitreous material as the envelope of the X-ray tube 14 rigidly affixed to the latter and forming a part thereof. This skirt extends from the point of connection to the envelope 14 slightly outwardly and upwardly to form a ring or collar surrounding the envelope having a slightly greater diameter than the latter.

The flange 28 is in this instance provided with a slightly tapering edge 34 about the periphery of the laterally extending portion thereof which is joined to the larger diameter portion of the skirt 33. These elements are united at this point in a manner well known to the art to form a metal to glass seal which is absolutely oil tight thus dispensing with the necessity of an oil resisting cement as in the modification previously described. The flange 28 may then be secured to the casing 5 in the same manner as stated relative to Figs. 1 and 2.

In Fig. 4, I have shown still another form of my invention for supporting the X-ray tube 110 to the container. In this particular embodiment I surround the X-ray tube envelope with a metal band 35 or make the same an integral part of the wall of the envelope by uniting the glass envelope thereto as is well known. 115 This metal band 35 is provided with a laterally extending ring 36 surrounding the band which is either rigidly secured thereto or may be a part struck up from the band itself.

The flange 28 is provided, in this instance, 120 with a laterally extending portion comprising a flexible metal collar 37 which is joined to the ring 36 and consequently to the tube envelope 14 forming therewith an oil tight seal. This reduces the rigidity between the tube and casing and absorbs, to a considerable extent, any jars or shocks to which the tube may unavoidably be subjected during shipment or operation of the apparatus. Moreover, due to the yieldable construction of the flange 28, displacement of 125 the tube in a longitudinal direction occurs following any tendency of the cooling and insulating material to change its volumetric capacity due to rises in temperature.

In view of the foregoing it readily becomes obvious to those skilled in the art that I have provided a shockproof X-ray unit that is rugged and compact and in which the possibility of an operator or patient accidentally contacting any high voltage parts is entirely obviated. Moreover, all high tension carrying parts are immersed in a cooling and insulating material having a high dielectric strength thus reducing the spacing therebetween and enabling the employment of a foreshortened X-ray tube.

Although the greater portion of the tube is immersed in the cooling and insulating medium the portion of the envelope through which the X-rays emanate is disposed exteriorly of the casing and medium thus preventing the filtering

- of the X-rays or in any way affecting the quality of the X-ray projected upon a patient or a sensitized film.
- Having described several specific embodiments 5 of my invention I do not desire to be limited thereto as various other modifications of the same may be made without departing from the spirit and scope of the invention as set forth in the appended claims.
- 10 What is claimed is:
1. In an electron discharge apparatus, the combination of a casing provided with a source of high potential electrical energy therein, an insulating and cooling medium enveloping said high potential source, an electron discharge tube formed at least in part of a vitreous hermetically sealed evacuated envelope having an anode and a filamentary cathode and adapted to be energized by said high potential source, 15 and means for supporting said discharge tube by said casing with the greater portion of the envelope of said tube immersed in said cooling and insulating medium and the remainder thereof disposed exteriorly of said casing, and said 20 means forming an oil tight seal with said envelope and said casing.
  2. In an electron discharge apparatus, the combination of a casing provided with a source of high potential electrical energy therein, an insulating and cooling medium enveloping said high potential source, an electron discharge tube formed at least in part of a vitreous hermetically sealed evacuated envelope having an anode and a filamentary cathode and adapted to be energized by said high potential source, and means for supporting said discharge device by said casing with the greater portion of the envelope of said tube and its anode terminal 25 immersed in said insulating and cooling medium, and the remainder of the envelope of said tube and its cathode terminal disposed exteriorly of said casing, said means forming an oil tight seal with the envelope of said tube and said casing.
  3. In an X-ray apparatus, the combination of a casing provided with a source of high potential electrical energy therein, an insulating and cooling medium enveloping said high potential source, an X-ray tube formed at least in part of a vitreous hermetically sealed evacuated envelope having an anode and a filamentary cathode and adapted to be energized by said high potential source, and means interposed between the envelope of said tube and said casing, for supporting said X-ray tube by said casing with the greater portion of the envelope of said tube immersed in said insulating and cooling medium and the remainder thereof disposed exteriorly of said casing, and 40 for forming an oil tight seal between said tube and said casing.
  4. In an electron discharge apparatus, the combination of a casing provided with a source of high potential electrical energy therein, an insulating and cooling medium enveloping said high potential source, an electron discharge tube having an hermetically sealed evacuated envelope formed at least in part of a vitreous material and provided with an anode and a filamentary cathode adapted to be energized by said high potential source, and means for securing said tube to said casing to form an oil tight seal therebetween with the greater portion of the envelope of said tube projecting into said casing and immersed in said insulating and cooling medium.
- cooling medium and the remainder thereof disposed exteriorly of said casing.
5. In an electron discharge apparatus, the combination of a casing provided with a source of high potential electrical energy therein, an insulating and cooling medium enveloping said high potential source, an electron discharge tube having an hermetically sealed evacuated envelope formed at least in part of a vitreous material and provided with an anode and a filamentary cathode adapted to be energized by said high potential source, and an oil tight flange secured to the envelope of said tube and engageable with said casing to form an oil tight seal therebetween and for supporting said tube with the greater portion of the envelope thereof disposed interiorly of said casing in said body of insulating and cooling medium and the remainder of said tube disposed exteriorly of said casing.
6. In an X-ray apparatus, the combination of a casing provided with a source of high potential electrical energy therein, an insulating and cooling medium enveloping said high potential source, an X-ray tube having an hermetically sealed evacuated envelope formed at least in part of a vitreous material and provided with an anode and a filamentary cathode adapted to be energized by said high potential source, and means forming an oil tight seal with said envelope and said casing, and for supporting said X-ray tube by said casing with the greater portion of the envelope of said tube and its anode terminal disposed interiorly of said casing in said body of insulating and cooling medium and the remainder of said envelope and the cathode terminal disposed exteriorly of said casing.
7. In an X-ray apparatus, the combination of a casing provided with a source of high potential electrical energy therein, an insulating and cooling medium enveloping said high potential source, an X-ray tube having an hermetically sealed evacuated envelope formed at least in part of a vitreous material and provided with an anode and a filamentary cathode adapted to be energized by said high potential source, and means secured to the envelope of said tube and to said casing to form an oil tight seal therebetween and for supporting said tube with the portion of said envelope from which X-rays emanate located exteriorly of said casing and the remainder of said envelope disposed interiorly of said casing and immersed in said cooling and insulating material.
8. In an X-ray apparatus, the combination of a casing provided with a source of high potential electrical energy therein, an insulating and cooling medium enveloping said high potential source, an X-ray tube energizable by said high potential source having an hermetically sealed evacuated envelope formed at least in part of a vitreous material and provided with an anode and a filamentary cathode therein and an anode stem, a heat dissipating means carried by said anode stem for dissipating heat from said anode during operation of said X-ray tube, and means forming an oil tight seal with the envelope of said tube and said casing, and supporting said X-ray tube with the portion of said envelope from which X-rays emanate disposed exteriorly of said casing and the remainder of said envelope and said heat dissipating means disposed interiorly of said casing and immersed in said cooling and insulating medium.

9. In an X-ray apparatus, the combination of a casing provided with a source of high potential energy therein, an insulating and cooling medium enveloping said high potential source, an X-ray tube energizable by said high potential source and having an hermetically sealed evacuated envelope formed at least in part of a vitreous material with an anode and a filamentary cathode therein, a flange adapted to be secured to the envelope of said tube and to said casing, means for securing said flange to the envelope of said tube comprising an oil resisting cement having a coefficient of expansion similar to said envelope, and means for securing said flange to said casing to form an oil tight seal therewith and to support said tube with the portion of said envelope from which X-rays emanate disposed exteriorly of said casing and the remainder of said envelope disposed interiorly of said casing and immersed in said insulating and cooling medium. 80
10. In an X-ray apparatus, the combination of a casing provided with a source of high potential energy therein, an insulating and cooling medium enveloping said high potential source, an X-ray tube energizable by said high potential source having an hermetically sealed evacuated envelope formed at least in part of a vitreous material and provided with an anode and a filamentary cathode, said envelope being formed in part of metal and provided with a flange flexibly secured thereto and forming an oil tight seal therewith for the purpose of preventing shocks from deleteriously affecting said tube, and means for securing said flange to said casing to form an oil tight seal therewith and to support said tube with the portion of said envelope from which X-rays emanate disposed exteriorly of said casing and the remainder of said envelope disposed interiorly of said casing and immersed in said insulating and cooling medium for cooling said tube during operation 100 thereof. 85
11. In an X-ray apparatus, the combination of a casing provided with a source of high potential electrical energy therein, an insulating and cooling medium enveloping said high potential source, an X-ray tube energizable by said high potential source having an evacuated hermetically sealed envelope formed at least in part of a vitreous material and provided with an anode and a filamentary cathode, said envelope being formed in part of metal and provided with a flange flexibly secured thereto and forming an oil tight seal therewith for the purpose of preventing shocks from deleteriously affecting said tube, and means for securing said flange to said casing to form an oil tight seal therewith and to support said tube with the portion of said envelope from which X-rays emanate disposed exteriorly of said casing and the remainder of said envelope disposed interiorly of said casing and immersed in said insulating and cooling medium. 90
12. In an X-ray apparatus, the combination of a casing provided with a source of high potential energy therein, an insulating and cooling medium enveloping said high potential source, an X-ray tube energizable by said high potential source having an hermetically sealed evacuated envelope formed at least in part of a vitreous material as said envelope, having a skirted portion contiguous therewith of the same vitreous material as said envelope, 95
